UNITED STATES PATENT OFFICE.

FRANK BRISCOE, OF PONTIAC, MICHIGAN, ASSIGNOR TO BRISCOE DEVICES CORPORATION, OF PONTIAC, MICHIGAN, A CORPORATION OF MICHIGAN.

CARBURETOR.

1,408,072.

Specification of Letters Patent. Patented Feb. 28, 1922.

Application filed November 12, 1920. Serial No. 423,591.

To all whom it may concern:

Be it known that I, FRANK BRISCOE, a citizen of the United States of America, residing at Pontiac, in the county of Oakland and State of Michigan, have invented certain new and useful Improvements in Carburetors, of which the following is a specification, reference being had therein to the accompanying drawings.

10 The invention relates to carburetors employing in their construction die cast parts, and has for its object the avoidance of certain defects incident to such construction. It has been found that many parts of the 15 carburetor can be formed by die castings containing chambers or passages for the carbureted mixture. On the other hand, where liquid fuel passages are formed in such castings, it is difficult to maintain the same leak- 20 proof, because of the typical occurrence of the blow holes in die castings, particularly where the liquid is under any head or pressure as, for instance, the feed line to the float chamber. With certain constructions as 25 heretofore made, the cover of the float chamber is formed integral with the main casing of the carburetor and of a die casting, while the fuel supply is through a passage in this cover controlled by the float valve. This 30 construction has the objection above referred to and has resulted in the leakage of the fuel past the float valve, thereby flooding the float chamber.

With the present construction I employ 35 substantially the same structure of die cast casing including the cover for the float chamber, but use in combination therewith a fitting of leak-proof material forming the fuel supply connection, the seat for the float 40 valve, and also a strainer and sediment chamber.

In the drawings:

Figure 1 is a cross-section through a carburetor to which my improvements are applied;

Figures 2, 3, 4 and 5 are perspective views of some of the parts detached.

A is a die cast member which includes a hollow portion B constituting the mixing 50 passage, and a centrally depending portion C for engaging the cup or bowl D of the float chamber and which is threaded at its lower end to receive the cap E which clamps said bowl. The fitting A also includes a 55 cover F which fits over the float chamber

and through which the fuel supply passes into said chamber.

To avoid dependence upon the die casting for any passage in the fuel line, I have devised a fitting for attachment to the cover F, 60 of the following construction: G is a post member, preferably formed of brass or other suitable metal, having a threaded lower end portion H for engaging a correspondingly threaded aperture in the cover. This member is provided with a collar or flange I which seats upon the top of the cover and above said collar a stem J of reduced diameter terminating in a threaded upper end portion K. The member is provided with a bore L ex- 65 tending from the lower end up into the portion J and having the counterbore below said portion J for forming an annular seat M. There are also provided a plurality of ports O through the walls of the portion J 70 communicating with the central bore. P is a cylindrical screen which is sleeved upon the portion J and is held out of contact therewith by annular shoulders J' at opposite ends thereof. Q is a member fitting over 75 the member G with its lower end resting upon the collar I, while its upper end fits about the threaded portion K. The member Q is in effect a T-fitting having the laterally-extending threaded nipple portion R for en- 80 gaging a coupling to the fuel supply line, said nipple communicating with the chamber which surrounds the post. To form a liquid tight joint between the member Q and the member G, a gasket S is placed upon the 85 collar I. There is also a gasket placed about the threaded portion K bearing against the upper end of the member Q and a clamping nut U engaging said threaded portion contacts with this gasket and seals the joint. 95

With the construction described the fuel supply line (not shown) is coupled to the nipple R and the stem W of the float valve engages the counterbore in the lower end of the member G seating against the shoulder 100 M. Thus when the float valve is in action, the incoming liquid in the fuel line is in no place in contact with the die cast part. Also, the liquid in passing into the float chamber is freed from any foreign substance by the 105 screen P and any sediment which collects will lodge in the chamber at the lower end of said screen. To increase the capacity of the sediment chamber without interfering with the action of the screen, the latter is 110

supported upon a ledge X, which is of polygonal form to provide a wrench hold for screwing the member G into engagement with the cap F. The corners of this ledge 5 X form spacers for properly centering the member Q, while the spaces intermediate the corners form the sediment chamber. The construction is one which can be made largely from bar stock by automatic machines and is therefore inexpensive to manufacture while it effectually cures the defects 10 incident to forming liquid passages in the die casting.

What I claim as my invention is:

- 15 1. In a carburetor, the combination with a die cast part including the cover of the float chamber, of a fitting formed of a leak-proof material secured to said cover and constituting a seat for the float valve, and a 20 connection for the fuel supply line.
2. In a carburetor, the combination with a die cast part including a cover for the float chamber, of a fitting secured to said cover and formed with a seat for the float 25 valve, a coupling for the supply line, a screen, and a sediment chamber.
3. In a carburetor, the combination with a die cast part including a cover for the float chamber, of a fitting comprising a post 30 member having an engagement with said cover and extending upward therefrom, said post being hollow and having a seat formed therein for the float valve and ports opening outward from the portion above said seat, 35 a screen surrounding said post, a hollow casing surrounding said screen and forming a sealing joint with said post, and a connection between said hollow casing and the supply line.
- 40 4. In a carburetor, the combination with a die cast part including a cover for the float chamber, of a fitting including a post member having a threaded lower end for engaging correspondingly threaded apertures 45 in the cover, a collar or flange above said threaded portion, a shank of reduced diameter above said flange terminating in a threaded upper portion, said post being hollow with an opening at the lower end and 50 being counterbored to form an annular seat therein for the float valve with ports opening outward from the portion above said seat, a screen surrounding said post and spaced from the shank thereof, a hollow member sleeved upon said post and spaced 55 from the screen, the lower end of said mem-

ber forming a sealing joint with said collar or flange on the post, and a clamping nut for engaging the threaded upper end of said post for securing said hollow member and 60 forming a sealing joint therewith, said hollow member constituting a coupling to the fuel supply line, and a chamber for containing the screen.

5. In a carburetor, the combination with 65 a die cast part including a cover for the float chamber, of a fitting comprising a post member having the threaded lower end for engaging the threaded aperture in the cover, a flange or collar above said threaded portion, 70 a reduced shank above said flange or collar terminating in a threaded upper end, said post being hollow and open at its lower end with a counterbore for forming an annular seat therein for engagement with the float 75 valve, and ports through the reduced portion above said seat, a polygonal portion on said post above said flange forming a wrench hold and a spacer, a hollow member sleeved upon said post and spaced from the shank thereof 80 by the corners of said polygonal spacer, a screen surrounding said reduced shank within said hollow member, and a clamping nut engaging the upper threaded portion of said post for securing said hollow member with 85 the sealing joint between the same and said post, said hollow member constituting a coupling to the fuel supply line, and a sediment chamber with pockets formed by the polygonal portion between the corners thereof 90 and below said screen.

6. In a carburetor, the combination with 95 a die cast part including a cover for the float chamber, of a post member of leak-proof material removably secured to said 100 cover and provided with a bore, said member having a counterbore at one end forming a seat for a float valve and having a plurality of ports formed therein, a screen surrounding a portion of the post member, a hollow 105 member sleeved upon the post member and having a connection for the fuel supply line, and a ledge carried by the post member beneath the screen for properly centering the hollow member and to provide a sediment 110 chamber.

In testimony whereof I affix my signature.

FRANK BRISCOE.
